UNITED STATES PATENT OFFICE.

JOSEPH GOLDENBERG, OF CINCINNATI, OHIO.

PIPE-BENDING DEVICE.

SPECIFICATION forming part of Letters Patent No. 664,943, dated January 1, 1901.

Application filed June 20, 1900. Serial No. 21,004. (No model.)

To all whom it may concern:

Be it known that I, JOSEPH GOLDENBERG, a citizen of the United States, residing at Cincinnati, in the county of Hamilton and State of Ohio, have invented certain new and useful Improvements in Pipe-Bending Devices; and I do hereby declare the following to be a full, clear, and exact description of the invention, such as will enable others skilled in the art to which it appertains to make and use the same.

My invention relates to pipe-bending devices.

The object of my invention is to provide an improved device of this character having a vise-frame adapted to admit between its jaws crooked or uneven pipe, as well as straight pipe of varying diameter, and to serve independently as a vise for such when needed for threading, fitting, or manipulating the same.

In the accompanying drawings, forming a part of this specification, Figure 1 is a perspective view. Fig. 2 is a front elevation. Fig. 3 is a side elevation. Fig. 4 is a top plan view.

Referring more particularly to the drawings, A denotes a casting forming the body of the device, having a base A' provided with lag-screws *a* for securing it to a board or plank. A² denotes a lug formed on the upper end of said body, A³ a lug formed on its face, and A⁴ a lug formed on the side of said body.

B denotes the vise-frame, consisting of two parallel arms B' B², rigidly secured at one end to a screw-threaded sleeve or tap B³, placed between them, which receives the screw-spindle C, having a head c, in which is fitted a sliding lever c'.

D denotes the movable jaw of the device. It is an oblong casting, as shown in Fig. 4, having flanges d d' upon its upper and lower sides, which embrace the vise-arms B' B² and serve to hold the jaw true as it slides between said arms. This jaw is attached to the screw C by a set-screw c'.

d d' denote set-screws which pass through jaw D and are secured to dies, as hereinafter mentioned.

E denotes a latch pivoted to the arm B' by a pivot-bolt e, as shown in Fig. 3.

F denotes a pivot-bolt passing through the arm B² of the vise and also through the lug

A³ on the body A. Thus the vise-frame is hinged to said body and is held in place thereon by the latch E engaging the lug A².

G denotes a die secured to the jaw D by screw-bolts d' d', as shown in Figs. 2 and 3, and provided with a semicircular groove g, as shown in Fig. 3. H denotes a die provided with a like groove h, arranged opposite and registering with the groove g. The die H is secured to the body A by screw-bolts h' h'. The die H is longer than the die G, and its extended end is curved or arc-shaped, as shown in Fig. 4, forming a bending-head. The inner curved side of this die bears against the lug A⁴. The grooves g and h extend throughout the length of the dies and form together a circular channel for the passage of the pipe, the entrance to which is shown in Fig. 3, (marked X.) K denotes a pipe-bending lever pivoted to the lug A⁴ by bolt k and having a pivoted die L secured thereto by pivot-bolt k'. The die L is formed with an arc-shaped groove, which faces or registers with the grooves in the dies G and H. K' denotes an arm bolted to said lever and connected to the pivot-bolts k k', forming with the inner end of said lever a yoke or housing for the die L. The arcs described by the radii drawn from the centers of the bolts k k' to the outer edges of the dies G and L are the same, so that any movement of the lever will cause the die L to ride over the arc-shaped end or bending-head of the die H.

It is evident that my invention can be used as a pipe-vise for holding pipe, and as the dies G and H are detachable other dies may be attached for pipes of varying diameters.

The operation of bending a pipe is as follows: If the pipe be straight and of proper diameter, it is inserted in the opening X and pushed through until the end to be bent projects out beyond the two dies G and H, as shown in dotted lines in Fig. 4. The lever is then turned to the position shown in full lines, which causes the die L to turn or bend the pipe around the bending-head of the die H to a full half-circle or to any smaller arc, if desired, by turning the lever only part way. If the pipe to be bent is not straight, by releasing the latch E the vise-frame, turning on its pivotal connection at A³, can be lowered or swung outward from the body A, thus sepa-

rating or enlarging the space between the dies G and H sufficiently to admit the pipe, when it can be clamped in position by the screw C preparatory to bending it.

Having shown and described my invention, what I claim, and desire to secure by Letters Patent, is—

In combination with the body portion of a bending device having an elongated pipe-engaging die, a vise-frame hinged to said body

portion carrying the sliding jaw of the vise, and means for securing said jaws in fixed relation.

In testimony whereof I affix my signature in presence of two witnesses.

JOSEPH GOLDENBERG.
